US0D1076966S

(12) **United States Design Patent** (10) Patent No.: **US D1,076,966 S**
(45) Date of Patent: ** May 27, 2025

(54) **DISPLAY SCREEN OR PORTION THEREOF WITH A GRAPHICAL USER INTERFACE**

(71) Applicant: **Beijing Zitiao Network Technology Co., Ltd.**, Beijing (CN)

(72) Inventors: **Ling Qiu**, Beijing (CN); **Yichen Li**, Beijing (CN); **Zhaoyuan Peng**, Beijing (CN); **Jian Sun**, Beijing (CN); **Sisi Pan**, Beijing (CN)

(73) Assignee: **Beijing Zitiao Network Technology Co., Ltd.**, Beijing (CN)

(**) Term: **15 Years**

(21) Appl. No.: **29/924,968**

(22) Filed: **Jan. 22, 2024**

Related U.S. Application Data

(62) Division of application No. 29/815,959, filed on Nov. 17, 2021, now Pat. No. Des. 1,029,871.
